(57) **CLAIM**

The ornamental design for a vacuum bag connector, as shown and described.

DESCRIPTION

FIG. 1 is a top perspective view of the vacuum bag connector of my claimed design;

FIG. 2 is a top side view of the vacuum bag connector of FIG. 1;

FIG. 3 is a bottom side view of the vacuum bag connector of FIG. 1;

FIG. 4 is a front side view of the vacuum bag connector of FIG. 1;

FIG. 5 is a back side view of the vacuum bag connector of FIG. 1;

FIG. 6 is a left side view of the vacuum bag connector of FIG. 1; and,

FIG. 7 is a right side view of the vacuum bag connector of FIG. 1.

The broken lines showing a vacuum bag illustrate environmental structure and form no part of the claimed design.

1 Claim, 7 Drawing Sheets
